LOOSE-LEAF BINDER

Fred D. Wedge, Oak Park, Ill., assignor to Wilson-Jones Company, Chicago, Ill., a corporation of Massachusetts

Application May 16, 1941, Serial No. 393,711

2 Claims. (Cl. 281—19)

This invention relates to a loose leaf binder, and particularly to the provision of a removable ring metal for the same.

It is an object of this invention to provide a case member with means whereby a ring metal may be readily attached or removed from the case member. It is a further object of this invention to provide simple and efficient means for maintaining a ring metal in a case member. Other objects of this invention will become apparent upon reading the following description, taken in conjunction with the accompanying drawings, in which:

Figure 1 is a fragmentary prospective view of a case member with a ring member in disassembled position;

Figure 2 is a longitudinal sectional view through the center of the binder showing the ring metal secured in one position;

Figure 3 is a view similar to Figure 2 showing the ring metal secured in reverse position; and

Figure 4 is a cross sectional view taken along the line IV—IV of Figure 2.

In the drawings, the reference numeral 2 indicates a back member to which a pair of cover members 3 is suitably hinged. A back plate 4 is secured to the back member 2 by means of a plurality of rivets or eyelets 5. The plate 4 is provided with a pair of elongated apertures 6 and 7.

The aperture 6 is provided with an end portion 8 of reduced width, and a raised flange 9 around the reduced portion. The aperture 7 is similar to the aperture 6 except that it is provided with an upstanding projection 10 at the end of the wide portion of the slot. The flanges 9 form a raised channel member at corresponding ends of the apertures 6 and 7. The plate 4 is also provided with an aperture 11 spaced from the aperture 6 a distance approximately equal to the length of the aperture 6. The aperture 11 is provided with an upstanding flange or wall 12.

The ring metal 13 includes a cover plate 14 in which a pair of toggle plates 15 is arranged in side by side relationship. The longitudinal edges of the cover plate are bent inwardly, as indicated at 16, to embrace the outer edges of the toggle plates and to provide the necessary spring force whereby the toggle plates are maintained in either of two positions. The toggle plates have mounted thereon a plurality of meeting ring sections 17 which remain open when the toggle plates are in one position, and form closed rings when the toggle plates are in their

other position. A trigger 18 may be provided at the end of the ring metal to facilitate manipulation of the rings.

Studs 19, secured to the under side of the cover plate 14, are spaced apart a distance equal to the center to center distance between the elongated apertures 6 and 7. Each stud is provided with a head 20 and a reduced neck portion 21. When the ring metal 13 is superimposed on the back plate 4 each stud registers with one of the apertures 6 or 7, and a sliding movement toward the narrow ends of the apertures 6 and 7 causes the neck portion 21 of each stud to engage the raised flange 9. The head 20 of each stud engages the other side of the flange 9 to prevent vertical movement of the ring metal relative to the back plate. The toggle plates 15 are recessed, as indicated at 22, to provide clearance space for the studs 19.

When the ring metal is positioned adjacent the back plate 4, with the studs 19 engaging flanges at the reduced ends of the apertures 6 and 7, a screw 23, threaded in the cover plate, may be screwed down to engage either the flange 12 or the raised portion 10, depending on whether the ring metal is in the position indicated in Figure 2 or that indicated in Figure 3. The toggle plates 15 are recessed, as indicated at 24, to provide clearance for the screw 23. By its engagement with the flange 12 or the raised portion 10, the screw 23 effectively prevents sliding movement of the ring metal in a direction away from the narrow ends of the apertures 6 and 7 so that the ring metal cannot be separated from the back plate 4 until the screw 23 is released.

It is obvious that the aperture 11 might be positioned anywhere along the back plate 4 and the same advantages as to reversibility of the ring metal would still be obtained, provided a similar aperture were positioned at the same distance from the plate 4. In this case the upstanding projection 10 would have no function and could be omitted. If the ring metal were provided with any number of rings permitting a space to be left at the center of the ring metal, the screw 23 might be positioned there, and a single aperture 11 would be sufficient. The projection 10 could be omitted in this case also.

Although I have described a preferred embodiment of my invention in detail, it will be understood that the description thereof is illustrative, rather than restrictive, as many details may be modified or changed without de-

parting from the spirit or scope of my invention.

Accordingly, I do not desire to be restricted to the exact construction described, except as limited by the appended claims.

I claim:

1. In a loose leaf binder, a back plate provided with a pair of elongated apertures having raised flanges adjacent one end thereof, said back plate being provided with another aperture spaced from one of said elongated apertures a distance approximately equal to the length of said aperture, said other elongated aperture having a raised portion adjacent its end opposite said raised flange, and a ring metal provided with a pair of studs engageable with said raised flanges and a screw engageable with said last mentioned aperture when the ring metal is in one position

and with said last mentioned raised portion when the ring metal is reversed.

2. In a loose leaf binder, a back plate, a ring metal slidably mounted on said back plate, said ring metal being reversible, said back plate having a pair of apertures each provided with an upstanding projection, said upstanding projection being spaced equidistant from opposite ends of said back plate, said ring metal having an aperture registering with one of said projections when said ring metal is in one position and with said other projection when said ring metal is reversed, and a screw engageable through said last mentioned aperture with either projection to prevent accidental separation of said ring metal from said back plate.

FRED D. WEDGE.
